UNITED STATES PATENT OFFICE.

ASA D. GILLETT, OF LAKE CITY, MINNESOTA, AND JAMES H. GILLETT, OF EVERETT, WASHINGTON.

VARIABLE CUT-OFF.

SPECIFICATION forming part of Letters Patent No. 694,057, dated February 25, 1902.

Application filed August 19, 1901. Serial No. 72,492. (No model.)

To all whom it may concern:

Be it known that we, ASA D. GILLETT, residing at Lake City, in the county of Wabasha and State of Minnesota, and JAMES H. GILLETT, residing at Everett, in the county of Snohomish and State of Washington, citizens of the United States, have invented certain new and useful Improvements in Variable Cut-Offs, of which the following is a specification.

Our invention relates to improvements in variable cut-offs for steam-engines for stern and side wheels for steamboats, and consists of the novel features of construction and arrangement hereinafter particularly described and claimed.

In the accompanying drawings, forming part of this specification, Figure 1 is a side elevation of the main cylinder and our improvements arranged in connection therewith, certain parts being broken away to better show the construction; and Fig. 2 is a top plan thereof.

In the drawings, A represents the piston-valve controlling the opening 2, leading into the end of the main cylinder 3. The piston A is connected by a rod 4 to a similar piston in the chest 5, the end of the rod 4 being connected with the usual operating mechanism. The operating mechanism connected with the rod 4, which includes the mechanism for reversing the engine, being part of the ordinary construction of the steam-engine of a stern or side wheel steamboat and forming no part of this invention, is not shown.

Arranged in the valve-chest 6, above the piston-valve A, is the cut-off valve B, said cut-off valve controlling the inlet-opening 7. To each of the valves B is connected a rod 8, which projects into the opening in the adjacent end of the guide-bar C. Fulcrumed upon the guide-bar C is the cross-bar 9, to the opposite ends of which are pivotally connected the rods 10, the opposite ends of said rods being connected by clamps 11 with the piston-

rods 8. To the cross-bar 9 is connected the lever 12, which in turn is connected to a rod 13, by means of which the cross-bar 9 is turned upon its support. It will be evident that as the cross-bar 9 is turned through the medium of the lever 12 and rod 13 the valves B will be drawn toward each other or separated, as the case may be, to change the point of cut-off. It will be understood that the guide-bar C travels uniformly, being actuated by an eccentric. (Not shown.) The valves B are actuated by the guide-bar C through the medium of the cross-bar 9, the rods 10, and clamps 11.

We claim—

1. In combination with main-valve steam-chests of the class described, of cut-off valve-chests arranged alongside said main-valve steam-chests, and having a direct port connection therewith, valves arranged in said cut-off valve-chests, rods connected with said valves, a cross-bar pivotally supported between the ends of said rods, and a connection between the opposite ends of said cross-bar and said rods.

2. In combination with a pair of main-valve steam-chests, arranged in longitudinal alignment, of a pair of cut-off valve-chests arranged alongside said main-valve chests and having direct communication therewith, valves arranged in said cut-off valve-chests, rods connected with said valves, and mechanism interposed between said rods for varying the relative positions of said cut-off valves, thereby changing the point of cut-off.

In testimony whereof we affix our signatures in presence of two witnesses.

ASA D. GILLETT.

JAMES H. GILLETT.

Witnesses as to signature of Asa D. Gillett:

J. W. MURDOCH,

J. S. HOWARD.

Witnesses as to signature of James H. Gillett:

CHAS. K. GREENE,

WM. R. STOCKBRIDGE.
